vale, Pa., a corporation of Pennsylvania

Application May 9, 1946, Serial No. 668,363

14 Claims. (Cl. 246—3)

1

My invention relates to railway traffic controlling apparatus, and more particularly to an improved system of circuits for use in centralized traffic control machines for the remote control of traffic movements in either direction on single track railroads, and is an improvement upon that shown in Fig. 1 of my application for Letters Patent of the United States, Serial No. 501,254, filed September 4, 1943, for Railway Traffic Controlling Apparatus, which issued as Patent No. 2,420,579, on May 13, 1947.

My invention is particularly adapted for use in a centralized traffic control system for manually controlling the signals of an absolute permissive block signaling system in which the signals are also governed automatically in accordance with traffic conditions by a system of reversible line circuits, controlled by continuous track circuits, as disclosed in my prior application above referred to. In systems of this character, the movement of traffic in either direction into a single track block is governed by head block signals, located at opposite ends of the blocks, and these blocks are divided into block sections, with intermediate signals for the two directions located at the junctions of the sections, all of which are controlled over a system of reversible line circuits in accordance with traffic conditions as manifested by the track relays of the sections in advance of the signals. Other opposing head block signals govern traffic movements into blocks which include passing tracks, where only the main track is provided with track circuits for controlling the signals, and since these blocks are relatively short, separate line circuits are provided for the two directions.

All of the head block signals are subject to manual control from a central point, such as a train dispatcher's office, by the provision of a code type communication system having field stations adjacent the track switches at the ends of the passing tracks for receiving control codes transmitted from the office, by which control relays for the switches and signals are operated in accordance with the positions of switch and signal levers at the office, and by which traffic relays are operated to govern the direction of energization of the reversible line circuit system for each single track block in accordance with the position of a master directional relay at the office. The station apparatus of the code system also serves to transmit indication codes to the office for indicating wayside conditions to the operator by lighting various lamps associated with a track

2

diagram, and for imposing restrictions upon the issue of control codes by the operator.

The centralized traffic control system also includes provisions for releasing electric locks for outlying hand throw switches by cooperation between the central office operator and the crew of a train.

One object of my invention is the provision of an improved system of traffic direction control for use in the centralized traffic control system referred to, or in other systems having generally similar requirements such as those employing cascade connected reversible track circuits in place of line circuits, as shown, for example, in Letters Patent of the United States, No. 2,344,333, issued March 14, 1944, to James J. Van Horn, for Railway Traffic Controlling Apparatus.

A feature of my invention is the provision of a signal clearing stick relay at the office for each head block signal for governing the transmission of control codes for clearing the signals, which relays are electrically interlocked to prevent the issue of signal clearing codes except when conditions are proper.

25 The traffic direction controlling apparatus of my invention functions in such a manner that the control of the traffic relays at the ends of the blocks requires no special action of the operator, but is effected automatically as a result of the usual operations for clearing a code controlled signal, these comprising the reversal of the signal lever for the head block signal which is to be cleared, followed by the operation of the associated code starting button whereby the transmission of a code for clearing the signal is initiated. In the event a reversal of traffic direction is required in order to permit the signal to clear, these operations result first in the movement of a master directional relay at the control office to a position designating the desired traffic direction, and then in the transmission of control codes to both ends of the block whereby the intermediate signals for the original traffic direction are put to stop, and then the intermediate signals for the desired direction are cleared automatically as the line circuit system becomes energized section by section. The control code received at the entering end of the block also operates a signal control relay thereby causing the head block signal at that end to clear in response to the energization of the line circuit system.

30 A feature of my invention resides in the control of the apparatus for reversing traffic, as above described, by a signal clearing relay, identified

with the entering head block signal, in such a manner that this apparatus becomes locked upon the issue of a signal clearing code, and then remains locked until indication codes are received which indicate that the block is unoccupied and that the head block signals are at stop.

Another feature of my invention involves the control of the signal indication relays so that they not only indicate the condition of the signals but also the condition of approach locking relays controlled thereby, by which the signals are electrically interlocked with the track switches and with the opposing signals at the distant end of the block, whereby the control of the traffic direction apparatus is made dependent upon the approach and time locking conditions in the field as reflected by these relays.

A further feature of my invention is the provision of a signal clearing relay for each leaving signal at the end of a single track block, for governing traffic movements into one of the adjoining passing tracks. This relay serves to prevent the inadvertent clearing of the leaving signal by a control code transmitted to its station when the code is initiated by the operation of the starting button for the entering signal at the opposite end of the block.

Another feature of my invention comprises an improved arrangement for unlocking a hand throw switch at an outlying location within the block by the transmission of control codes to both ends. These codes may be initiated by the operation of a control lever for the switch only when the entering signals at the ends of the block are at stop, and these codes are rendered incapable of clearing the entering signals even though the signal levers are inadvertently reversed before they are transmitted.

Other objects, purposes and features of my invention will be pointed out as the description proceeds.

I shall describe one form of apparatus embodying my invention, and shall then point out the novel features thereof in claims.

Referring to the accompanying drawings, Fig. 1 shows the control levers and circuits embodying my invention contained in one section of the office control machine of the centralized traffic control system, including the control panels for two stations located at opposite ends of a single track block as indicated by the miniature track diagram at the top of the view. Fig. 1 also shows the control apparatus for the right-hand end of the double track block, extending to the left, as well as that for the left-hand end of the double track block at the right of the single track block shown, it being understood that the operator's control board is made up of a plurality of sections each generally similar to Fig. 1.

Figs. 2A and 2B show a plan of the stretch of railway track corresponding to Fig. 1, together with the wayside circuits and apparatus. The wayside circuits as shown correspond generally to those of Figs. 2A, 2B and 2C of my prior application hereinbefore referred to, but as here shown they are arranged in a condensed form and the circuits for the control of the track switches 1W and 3W are omitted, since these have no bearing on the present invention.

To simplify the drawings, in lieu of showing the various sources of current for energizing the relays, I have shown only their terminals, the positive or supply terminal being identified by the reference character B and the negative or com-

mon return terminal by the reference character C, in each instance. A number of the relays shown, and the signal mechanisms as well, are of the polarized type, operable to different positions in accordance with the relative polarity of the current in their windings, and it is to be understood that each such device as shown is so polarized that its left-hand contacts close when terminal B is applied to the left-hand terminal of its winding.

Similar reference characters refer to similar parts in each of the views.

Briefly described, my invention relates to apparatus for governing the operation of centralized traffic control systems of the code type, for single track railroads, the primary purpose of which is to prevent improper manipulation due to the unavoidable lapse of time between the issue of controls and the reception of return indications. My invention is embodied in apparatus at the control office interposed between the operator's levers and the conventional code transmitting apparatus, and includes a signal clearing relay LM or RM for each lever for a signal governing movements into a single track block, a corresponding relay LG or RG for each lever for a signal governing movements out of a single track block, and a repeating relay WLP for each lever for controlling the operation of an outlying track switch. These relays are interlocked one with another so as to prevent the issue of conflicting controls, and the relays LM and RM govern a traffic direction control relay LP, employed conventionally in systems of this character, in a more positive manner than heretofore, due in part to the fact that these relays are controlled not only by their respective signals and the adjacent track relays but also by the signal control relays LHS or RHS and by approach or time locking relays LAS and RAS at the field stations. Additionally, the relays LM and RM, and also the relays LG and RG, function in such a manner as to insure against the inadvertent clearing of their respective signals under various conditions.

The code control system

The code system employed for communication between the office and the wayside stations corresponds generally to that shown in Letters Patent of the United States No. 2,229,249, issued January 21, 1941, to Lloyd V. Lewis, for Remote Control Systems, and specifically to a modification thereof described in Letters Patent of the United States No. 2,411,375, issued November 19, 1946, to Arthur P. Jackel, for Remote Control Systems, and in a booklet entitled "Time Code Control System, Manual 506-A," published by the Union Switch and Signal Co., of Swissvale, Pa.

Consideration of the detailed mode of operation of the code system is not needed for an understanding of my invention, and it is deemed sufficient to point out that the code system provides seven channels for the transmission of controls from the office to a selected station, and seven other channels for the transmission of indications from any station to the office, only one station at a time, over a single line circuit, without interference. For simplicity, the various channels are designated by numbers and are represented herein by direct wire connections. Each control code transmitted from the office is initiated by the manual energization of a starting relay, such as the relay O1ST or O3ST, Fig. 1, of which one is provided for each office panel.

Each starting relay is picked up by the momentary closing of a contact *a* or *b* of a starting button 1STB or 3STB or of the switch lock lever 2WL. Lever 2WL is of the "push-turn" type, its contacts *a* and *b* closing whenever its rotary contacts *c* and *d* are moved from one operative positive to another. Each starting relay initiates a code by closing its front contact *c*, to pick up the master relay OM of the code system, by which the transmission of the code is governed, and is held energized over a stick circuit until its code is transmitted, in the manner described in Patent No. 2,229,249.

Each control code includes a distinctive code call by which a selector relay OIS or O3S for the same panel, together with a delivery relay 1D, Fig. 2A, or relay 3D, Fig. 2B, at the corresponding field station No. 1 or No. 2, are energized, only one panel and station at a time, thereby establishing the control channels for communication between the selected panel and station. At the office each channel is supplied with current or not, depending upon the control to be effected, and at the selected station a group of polar stick relays comprising a traffic relay 2RFS or 4LFS, a switch lock control relay 2WLS, and the signal control relays 2RHS and 2LHS or 4RHS and 4LHS, and other similar relays, not shown, are operated to normal or reverse in accordance with the condition of a series of register relays 1F2, 1F4, etc., interposed in the channels. Of the seven control channels which the system provides, only channels 2, 4, 5 and 7 are shown herein.

The master directional relay by which the direction of traffic movements in the single track block is governed is relay LP, Fig. 1. At stations No. 1 and No. 2, respectively, the traffic relays 2RFS and 4LFS are operated over channel 2 by different codes to a position corresponding to that of relay LP. At station No. 1, the switch lock control relay 2WLS for the hand throw switch 2W is controlled over channel 4, by a repeating relay 2WLP for the switch lock lever 2WL of Fig. 1, relay 2WLP also controlling the traffic relay 4LFS over channel 2, in response to a code initiated by the operation of lever 2WL. When relay 2WLP is in its released position, if contact *c* of relay LP is in its left-hand position as shown, it connects terminal B over back contact *j* of a direction locking relay LPS and contact *e* of the selector relay OIS to channel 2 to energize relay 1F2, Fig. 2A, so that when the delivery relay 1D is energized, relay 2RFS is operated over front contacts of relay 1F2 to close its left-hand contacts. Since channel 4 is open, relay 2WLS is operated over back contacts of relay 1F4 to also close its left-hand contacts. Relay 3F2, connected to channel 2 at station No. 2 is not energized by the code transmitted to that station because the connection from terminal B at contact *c* of relay LP over back contact *k* of relay LPS and contact *e* of relay O3S to channel 2 is open, consequently when the delivery relay 3D is operated, relay 4LFS is energized in the normal direction to close its left-hand contacts. On the other hand, when contact *c* of relay LP is in its right-hand position, relay 1F2 is released and relay 3F2 is energized, so that relays 2RFS and 4LFS are operated to close their right-hand contacts by their respective delivery relays 1D and 3D.

When relay 2WLP is energized, relay 2RFS will be operated to a position corresponding to that of relay LP as above described, but since

terminal B at contact *a* of relay 2WLP is connected over contact *e* of relay O3S to channel 2, relay 3F2 is energized and relay 4LFS is operated to close its right-hand contacts regardless of the position of relay LP. Also terminal B at contact *b* of relay 2WLP is connected over contact *h* of relay OIS to channel 4 to energize relay 1F4, causing relay 2WLS to be operated to close its right-hand contacts in response to the code received at station No. 1.

The head block signals are controlled primarily by the three position signal levers 2SG and 4SG, which levers, by means of their contacts *a* and *b* also control relay LP. The signal controls are transmitted over channels 5 and 7, and to properly correlate the controls for the entering signals for the single track block with the traffic direction apparatus and to interlock these controls with those for the hand throw switch and for the leaving signals at the same station, a pair of signal clearing relays 2RM and 4LM is provided.

To transmit a control code for clearing signal 4LA or 4LB, the contacts of relay LP must occupy their left-hand position corresponding to the right-to-left traffic direction. If lever 4SG is moved to its left-hand reverse position and the starting button 3STB is operated under this condition, the starting relay O3ST is energized over contact *a* of button 3STB to initiate a control code by which relays OM and O3S at the office and relay 3D at station No. 2 are energized. Relay O3S completes a circuit from terminal B at front contact *h* of relay OM over back contact *d* of relay 2WLP, the left-hand contact *d* of relay LP, front contact *d* of relay O3S, contact *c* of lever 4SG, back contact *b* of relay 4RG through relay 4LM to terminal C at back contact *e* of relay 3TK, and relay 4LM picks up to complete a stick circuit over its front contact *a* which extends to terminal B at back contact *d* of relay 2-4Z.

Channel 5 is energized over the connection from terminal B at the left-hand contact *c* of relay LP, back contact *f* of relay 2-4Z, front contact *e* of relay 4LM, the left-hand contact *d* of lever 4SG and contact *f* of relay O3S, whereby relay 3F5, Fig. 2B, is energized and when relay 3D is operated, the signal control relay 4LHS is energized in the reverse direction, closing its right-hand contacts to complete circuits for clearing signal 4LA or 4LB, depending upon the position of switch 3W, as hereinafter explained.

To transmit a control code for clearing signal 2RA or 2RB, the contacts of relay LP must occupy their right-hand position corresponding to the left-to-right traffic direction, and if lever 2SG is then moved to its right-hand reverse position and the starting button 1STB is operated, the starting relay O1ST is energized over contact *a* of button 1STB to initiate a control code by which relays OM and OIS at the office and relay 1D at station No. 1 are energized. Relay OIS completes a circuit to pick up relay 2RM extending from terminal B at front contact *h* of relay OM over back contact *d* of relay 2WLP, the right-hand contact *d* of relay LP, contact *d* of relay OIS, contact *c* of lever 2SG, back contact *b* of relay 2LG through relay 2RM to terminal C at contact *e* of relay 1TK, and relay 2RM completes a stick circuit extending to terminal B at back contact *b* of relay 2-4Z.

In this code, channel 7 is energized over connection from terminal B at the right-hand contact *c* of relay LP, back contact *e* of relay

2-4Z, front contact *e* of relay 2RM, the right-hand contact *d* of lever 2SG and contact *g* of relay O3S, whereby relay 1F1, Fig. 2A, is energized and the signal control relay 2RHS is operated to reverse by relay 1D, to clear signal 2RA or 2RB as hereinafter described.

When the signal clearing relay 2RM or 4LM is energized, it opens its back contact *d* in the circuit for relay 2WLP, thereby preventing the operator from issuing a code for unlocking switch 2W, and also opens a back contact *e* in the circuit for the associated relay 2LG or 4RG which governs the clearing of the opposing head block signal at the same station. Relay 2RM or 4LM when energized also opens its back contact *b* in the circuits for relays LP and LPS to insure that these relays will be locked deenergized from the time the operator issues a signal clearing code until relay LP becomes locked by the resulting change in traffic conditions, as occurs when a train accepts the cleared signal and enters the single track block to cause the transmission of indication codes by which relays 3TK, 4LBK, 2RBK and 1TK are energized as herein-after explained. Accordingly, relay 2RM or 4LM is arranged to be released automatically by the track indication relay 1TK or 3TK in response to the indication code transmitted when the train governed by the signal which relay 2RM or 4LM controls enters the first track section of the block.

The release relay 2-4Z is provided to enable relay 2RM or 4LM to be released manually, by the transmission of a signal stop code, by which relay 2RHS or 4RHS is restored to its normal position. Assuming for example that while relay 4LM is energized, the operator restores the corresponding signal lever 4SG to normal and presses button 3STB to initiate a control code, the selector relay O3S is operated and relay M8P releases momentarily to pick up relay 2-4Z over the circuit extending from terminal B at back contact *a* of relay M8P, contact *c* of relay O3S, contact *g* of lever 4SG and contact *e* of relay 4LM through relay 2-4Z to terminal C. Relay 2-4Z may also be picked up by restoring lever 2SG to normal and operating button 1STB, while relay 2RM is energized, as will be clear from the drawings. Relay M8M is a normally energized relay controlled by relays O8 and OM of the code system, and is released only during the eighth step of a control code, that is to say, during a step immediately preceding the series of steps during which the control channels are established, and serves also to release the energized starting relay O3ST or O1ST. Relay 2-4Z is held energized over a stick circuit including contact *e* of relay 2RM or 4LM, the signal lever contact *g* and its own front contact *a* or *c*, and by closing its front contact *b* or *d*, relay 2-4Z extends the stick circuit for the energized relay 2RM or 4LM to terminal B at the back contact *h* of the associated delivery relay O1D or O3D. Relay 2RM or 4LM is thereby placed under control of the code indication system and is released, as hereinafter explained, only upon the reception of a code which indicates that the corresponding signal control relay 4LHS or 2RHS has been restored to normal and that the signals controlled thereby are at stop and are not approach locked so as to prevent a change in route. When relay 2RM or 4LM releases, its contact *e* opens the circuit for relay 2-4Z so that relay 2-4Z also releases.

In the event the operator is unable to release relay 2LM or 4RM by the operation of relay

2-4Z as above described, he may release relay 2-4Z by reversing the signal lever as required to reestablish the original route, the lever contact *g* being included in the stick circuit for relay 2-4Z as well as in its pick-up circuit, for that purpose.

The circuits above described including the signal clearing relays 2RM and 4LM and the release relay 2-4Z is an improvement upon those for a generally similar purpose disclosed in an application for Letters Patent of the United States, Serial No. 592,947, filed May 10, 1945, by Frank T. Pascoe and Arthur L. Jerome, For Traffic Direction Control Apparatus for Use in Centralized Traffic Control Systems for Single Track Railroads, which has issued as Patent No. 2,528,073, dated October 31, 1950.

The signal clearing relays 2LG and 4RG control the leaving signals for the single track block, these signals also constituting the head block or entering signals for the double track blocks at the opposite ends of the single track stretch shown.

To transmit a control code for clearing signal 2LA or 2LB, lever 2SG is moved to its left-hand position and the starting button 1STB is operated, completing a circuit from terminal B at the left-hand contact *e* of lever 2SG over contacts *e* of button 1STB and relay 2RM through relay 2LG to terminal C at contact *e* of the track indication relay 1TK. Upon the release of the starting button, relay 2LG is held energized over a stick circuit including its own front contact *a* having one connection to terminal B at back contact *e* of button 1STB and another at the left-hand contact *e* of lever 2SG. Contact *b* of relay 2LG opens the pick-up circuit for relay 2RM. In the control code transmitted when relay 2LG is energized, channel 5 is connected to terminal B over contact *c* of relay 2LG to energize relay 1F5, Fig. 2A, so that when relay 1D is operated relay 2LHS is energized reverse to clear signal 2LA or 2LB. Relay 2LG is arranged to be released automatically by the track indication relay 1TK when a train accepts signal 2LA or 2LB and enters the first track section of its route, and may also be released manually by restoring lever 2SG to its normal position and operating button 1STB which operations also cause the transmission of a control code to restore relay 2LHS to normal, thereby restoring the operated signal 2LA or 2LB to its stop position.

Relay 4RG is similarly controlled by button 3STB, in accordance with the position of lever 4SG and when relay 4RG is energized, its contact *b* opens the pick-up circuit for relay 4LM, while its contact *c* connects terminal B to channel 7 to pick up relay 3F7 to enable relay 3D to operate relay 4RHS to reverse to clear signal 4RA or 4RB.

The circuits for the relays 2LG and 4RG above described correspond generally to those for similarly designated relays disclosed in an application for Letters Patent of the United States, Serial No. 648,716, filed February 19, 1946, by James I. Grammer, for Centralized Traffic Control Systems.

Each signal control relay such as relay 2RHS or 2LHS is arranged to be restored to normal upon the release of the track relay, such as relay 1TR, when a train enters the first track section in advance of the signal, and is then governed by a track storage relay, such as relay 1TKS, of the code indication system, so that the signal control relay is prevented from responding to a

signal clearing code after the detector section has been entered by a train, until an indication of its occupancy has been transmitted to the office in accordance with an arrangement disclosed in an application for Letters Patent of the United States, Serial No. 649,598, filed February 23, 1946, by Arthur L. Jerome, Lloyd V. Lewis and Frank T. Pascoe, for Centralized Traffic Control Systems.

The circuits for the master directional relay LP as disclosed herein differ from those of my prior application and are arranged like those disclosed in an application for Letters Patent of the United States, Serial No. 640,753, filed January 12, 1946, by Lloyd V. Lewis, for Railway Traffic Controlling Apparatus, which issued as Patent No. 2,484,716 on October 11, 1949, in that they include contacts *d* of the starting buttons 1STB and 3STB, as well as contacts *b* and *c* of a normally deenergized direction locking relay LPS. When the single track block is unoccupied, the track indication relays 1TK and 3TK which indicate the condition of the switch sections and the block indication relays 2RBK and 4LBK which indicate the condition of the intervening single track stretch are all released, so that the lamps 1TKE, BKE and 3TKE in the track diagram controlled by these relays are all dark, while the direction indicator lamp LFE or RFE is lighted to indicate the position of relay LP. If the signal clearing relays 2RM and 2LM and the switch lock control relay 2WLM are released and lever 4SG is in its normal or right-hand position, relay LPS may be energized by operating lever 2SG to the right when lamp LFE is lighted to indicate that the opposing traffic direction is established, in which case the closing of the lever contact *b* completes a circuit from terminal B over back contacts *b* of relays 2RBK, 4LBK, 1TK, 3TK, 2RM and 4LM, right-hand contact *b* of lever 2SG, contact *a* of lever 4SG, left-hand contact *b* of relay LP, back contact *a* and winding of relay LPS to terminal C at back contact *e* of relay 2WLP. The circuits for the two directions are similar, and when lamp RFE is lighted, relay LPS may be energized by operating lever 4SG to the left under corresponding conditions to complete a branch of the circuit just traced which includes the normal or left-hand contact *a* of lever 2SG, the left-hand contact *b* of lever 4SG and the right-hand contact *b* of relay LP. When relay LPS picks up, it becomes disconnected from its pick-up circuit by the operation of its contact *a*, and is held energized over a stick circuit having multiple connections to terminal B at back contacts *c* of the starting relays O1ST and O3ST, so that relay LPS is held energized until control codes have been initiated, or stored for transmission, to the stations at both ends of the block.

If lever 2SG is operated to the right while lamp RFE is lighted, or if lever 4SG is operated to the left while lamp LFE is lighted, in order to clear a signal for a train movement in the direction already established, relay LPS remains released and the pressing of the starting button 1STB or 3STB then completes a circuit at its contact *a* only, whereby the associated starting relay O1ST or O3ST is energized, but when relay LPS is energized by the operation of a signal lever as described, the pressing of the starting button associated with that signal lever completes three other circuits, in addition. The closing of contact *c* of the operated starting button completes a circuit over contact *f* of relay LPS to energize a block repeating stick

relay BKS over back contact *f* of relay 2WLP, and the closing of contact *d* of the operated starting button completes a circuit over contact *b* or *c* of relay LPS for operating relay LP to the position designating the traffic direction to be established, while the closing of contact *b* of the operated button completes a circuit over the reverse contact *f* of the operated signal lever and contact *g* or *h* of relay LPS for energizing the starting relay O1ST or O3ST of the adjoining panel for the station at the opposite end of the block.

The stick circuit for relay LPS is opened as soon as both starting relays are energized, so that relay LPS releases, its pick-up circuit remaining open due to the change in the position of contact *b* of relay LP. It follows that two codes are initiated to operate the traffic relays 2RFS and 4LFS, respectively, over channel 2, to positions corresponding with that of relay LP.

The energization of relay O1S or O3S during the transmission of the code to the entering end of the block for the direction determined by relay LP causes relay 2RM or 4LM to become energized, as hereinbefore described, locking relays LP and LPS deenergized.

It will be seen that relay LP is free to be operated only when the block is unoccupied, as indicated by the reception of codes which reflect the energized condition of the reversible line circuit system by releasing the block indication relays 2RBK and 4LBK. The interruption of the wayside circuits by the traffic relays 2RFS and 4LFS renders them incapable of indicating the unoccupied block condition while the traffic direction is being changed, but during this period, it is desirable to permit relay LP to remain operable to either position so that the original traffic direction can be restored if the operator so desires, due to a change in orders or if the reversal cannot be effected, due to a fault. This is accomplished by the provision of the block repeating relay BKS, which is energized along with relay LP as described, and "stores" the block clear indication, in effect, to maintain relays LP and LPS operable, by closing its front contact *b* bridging the back contacts *b* of relays 2RBK and 4LBK in the circuits for relays LP and LPS until the wayside circuits are reestablished. When relay BKS picks up, it closes circuits momentarily over its contacts *d* and *e* to pick up the block indication relays 2RBK and 4LBK locally, placing them in condition to be released by codes indicating the unoccupied block condition, and the closing of the front contacts *b* of the block indication relays 2RBK and 4LBK completes a stick circuit for relay BKS, which relay therefore is held energized until both block indication relays release to indicate the reenergization of the line circuit system. During the period of traffic reversal, the circuits for the direction indication lamps LFE and RFE and for the block indication lamp BKE are all held open at back contact *c* of relay BKS so that an occupied block indication is not displayed and this period is distinctively indicated on the track diagram by the cancellation of the directional indication.

The operation of the switch lock lever 2WL is also effective to initiate the transmission of codes to both ends of the block, its contacts *a* and *b* closing momentarily to energize the starting relays O1ST and O3ST whenever lever 2WL is rotated from one operating position to another. Contact *d* of lever 2WL controls a repeating re-

lay 2WLP by which the circuits governed by relay 2WLP are interlocked by those controlled by the signal levers, that is, the circuit for relay 2WLP includes back contact *d* of relays 2RM and 4LM, and the circuits for relays LPS and BKS include back contacts *e* and *f* of relay 2WLP, while the circuits for relays 2RM and 4LM include back contact *d* of relay 2WLP. When relay 2WLP becomes energized, its contact *c* completes a branch of the circuit for relay LP including contact *c* of lever 2WL over which relay LP may be energized in either direction to place it in a position designating the desired direction of traffic movement for a train entering the block via switch 2W, while contacts *a* and *b* of relay 2WLP control the energization of channels 2 and 4 as already described. Since relay BKS is not operated, lamp LFE or RFE is lighted to indicate the position of relay LP and the reversal of the switch lock control relay 2WLS by one of the codes initiated by the operation of lever 2WL causes an indication code to be transmitted by which relay 2RBK is energized to light lamp BKE and to lock relay LP in its last operated position. Lamp BKE remains lighted, and relay LP is locked deenergized until relay 2WLS is restored to normal by returning lever 2WL to its normal center position.

In prior systems employing the master directional relay LP it has been necessary to include back contacts of the signal indication relays 2RHK and 4LHK in the circuits for relays LP and 2WLP in order to insure that these relays are locked deenergized when an entering head block signal has been cleared for an approaching train. However, it has been found desirable to modify the control of the signal indication relays as hereinafter described, in order to provide additional information of advantage to the operator by arranging them to indicate also the condition of the signal control relays and of the approach locking relays associated with the signals, so that he is enabled to avoid delays resulting from attempts to set up unavailable routes or to reverse traffic under improper conditions, and when so controlled, the operation of these relays is such that they would at times unnecessarily restrict the operation of relays LP and 2WLP.

This difficulty is overcome by the provision of the signal clearing relays 2RM, 2LG, 4LM and 4RG as herein disclosed and by the control of relays LP and 2WLP by relays 2RM and 4LM as shown herein instead of by relays 2RHK and 4LHK as heretofore.

The block signaling system

Considering now the wayside circuits of Figs. 2A and 2B, when Fig. 2B is placed at the right of Fig. 2A, these views show the circuits for a typical single track block extending from the head block signal 2RA or 2RB to the opposing head block signal 4LA or 4LB, which as shown is divided into three block sections and is provided with the intermediate signals 21, 22, 23 and 24.

By placing Fig. 2B at the left of Fig. 2A, these views show the circuits for a typical block including the main track of the double track stretch between the head block signals 4RA and 2LA.

The head block signals are to be understood to be of the searchlight type, each having an operating mechanism identified by the reference character G prefixed by the signal designation.

such as the mechanism 4LAG for signal 4LA. Each signal mechanism when energized in a normal or reverse direction conditions its signal to indicate proceed or caution, and when deenergized, to indicate stop. The intermediate signals 21, 22, 23 and 24 are assumed to be of the color light type, having lamps, not shown, for indicating proceed, caution or stop. The lamp circuits for the intermediate signals as well as the mechanisms G for the head block signals are governed by polarized relays, each identified by the reference character HD prefixed by the designation of the corresponding signal. The signal relays HD for the signals for the single track block are all controlled over the reversible line circuit system, which as shown, comprises three cascade connected line circuits corresponding to the three block sections, the line circuit for each section including front contact of the track relays TR for the adjacent track sections. Each such signal relay HD is arranged to be energized in series with an approach relay AR which governs the lighting of of the next signal in advance in a well-known manner, by means not shown.

The signal relays 4RHD and 2LHD, which govern the main line head block signals 4RA and 2LA, are normally energized over separate line circuits including the line wires 40, 41, 42 and 43 and front contacts of the track relay 6TR for the main track section. Signals 2LB and 4RB, for governing traffic movements at slow speed into the side track are governed in accordance with traffic conditions by the detector section track relays 3TR and 4TR, respectively, in a manner hereinafter explained. Relays 4RHD and 2LHD are also adapted to serve as approach lighting relays for signals 4LA and 2RA, while signals 4LB and 2RB are lighted continuously, in the absence of track circuits in the passing track.

Each signal relay for an intermediate signal, such as relay 21HD, when energized supplies current of normal polarity to the line circuit for the corresponding relay, such as relay 23HD, for the next signal in the rear, and has associated therewith the usual directional stick relay, such as relay 21S, which becomes energized when a train passes the corresponding signal at proceed or caution. Each directional stick relay when energized closes its front contacts to supply current of reverse polarity to the line circuit for the next section in the rear, and is held energized only until the associated signal relay HD is again energized. At the ends of the block, the polarity of the current supplied to the line circuit system is controlled by a pole changer relay, such as relay 2LAPC or 4RAPC, controlled by the leaving signal 2LA or 4RA, and the line circuit also includes a front contact of an approach locking relay 2RAS or 4LAS, which is controlled by the stop indication relay 2RGP or 4LGP for the adjacent entering signals as well as by their control relay 2RHS or 2LHS and by suitable time locking apparatus, as hereinafter described, by means of which the clearing of the opposing signals is prevented except when traffic conditions are proper.

As shown, the contacts *a* and *b* of the traffic relays 2RFS and 4LFS occupy their left-hand positions and the sections of the reversible line circuit system are thereby energized in cascade at their left-hand ends as required for traffic movements from right-to-left. More particularly, the left-hand contacts *a* and *b* of relay 2RFS connect terminals B and C of the local

source of current at station No. 1 over back contacts *a* and *b* of relay 2LAPC and front contact *d* of relay 2RAS to the left-hand section of the line circuit system, whereby current is supplied over the front contacts *a* and *b* of the track relays 1TR and 2TR, the line wires 28 and 29 extending to the location of signals 21 and 22, and over front contacts *a* and *b* of the track relay 21TR and back contacts *a* and *b* of relays 22S and 22HD, to energize the signal relay 21HD in series with the approach relay 2LAR. Relay 21HD is energized in the reverse direction to condition signal 21 to indicate caution, when signal 2LA indicates stop or caution, while relay 21HD is energized in the normal direction to condition signal 21 to indicate proceed, when signal 2LA indicates proceed, in which case the closing of front contact *G* of mechanism 2LAG causes relay 2LAPC to assume its energized position. The closing of the front contacts *a* and *b* of relay 21HD connects terminal B of the local source of current at the location of signals 21 and 22 to the intermediate section of the line circuit system extending to the location of signals 23 and 24, the connection to terminal B including a back contact *d* of relay 22HD, the winding of relay 21AR and front contact *d* of relay 21TR, whereby current is supplied over front contacts *a* and *b* of relay 21HD, back contacts *a* and *b* of relay 21S, front contacts *a* and *b* of the track relay 22TR, line wires 30 and 31, front contacts *a*, *b*, *c* and *d* of a normally energized indication relay 2NWP for the hand throw switch 2W, line wires 32 and 33, front contacts *a* and *b* of the track relay 23TR, back contacts *a* and *b* of relays 24S and 24HD to relay 23HD. The signal relay 23HD is thereby energized in the normal direction, in series with the approach relay 21AR, to condition signal 23 to indicate proceed. The closing of front contacts *a* and *b* of relay 23HD completes a generally similar circuit from terminals B and C of the source at the location of signals 23 and 24, whereby current is supplied over front contacts of the track relays 24TR, 24TR and 3TR and the line wires 34 and 35 for the third section of the block, to energize the signal relay 4LHD in the normal direction, over the left-hand contacts *a* and *b* of the traffic relay 4LFS, in series with the approach relay 23AR.

The signal circuits are governed in accordance with the position and locked condition of the track switches 1W and 3W by the usual switch repeating relays, such as the relays 1NWP and 3NWP which are energized only when their respective switches are locked normal, and relays 1RWP and 3RWP which are energized only when the switches are locked reverse.

When the signal control relay 4LHS is operated to reverse by code, with relays 3TR, 3NWP and 4LHD energized, or with relays 3TR and 3RWP energized, a block repeating relay 4BPR at station No. 2 becomes energized, its circuit extending from terminal B at the normal contact *b* of relay 4RHS over the reverse contact *b* of relay 4LHS, front contact *b* of relay 4LHD or front contact *g* of relay 1RWP, back contact *a* of relay 3RWP or 3NWP, front contact *a* of relay 3NWP or 3RWP and front contact *d* of a repeating relay 3TP of the track relay 3TR through relay 4BPR to terminal C.

The approach locking relay 4LAS, which is normally energized over a stick circuit including its winding and front contact *a* and extending over a front contact of relay 4LGP to terminal B at contact *a* of relay 4LHS, is released in response to the reversal of relay 4LHS, provided

relay 4BPR is energized thereby, as will be clear from the drawing. The closing of back contact *c* of relay 4LAS completes a circuit for mechanism 4LAG or 4LBG depending upon whether switch 3W is normal or reverse, to clear signal 4LA or 4LB.

The circuits for mechanisms 4LAG and 4LBG extend from terminal B at the reverse contact *a* of relay 4LHS over front contact *a* of relay 4BPR, contacts *c* of relays 4RAS, 3TER and 4LAS, the neutral contact *c* and the pole changer contacts *e* and *f* of relay 4LHD, over contacts *c* of relays 3NWP and 3RWP through mechanism 4LAG or 4LBG to terminal C at contact *c* of relay 4LHS.

It will be seen that the block repeating relay prevents the release of the approach locking relay 4LAS in response to the reversal of the corresponding signal control relay 4LHS unless a route is available so as to allow the signal to be cleared. If a route is not available, the operator may restore the signal control relay to normal and then establish a different route without being penalized by a delay due to the time locking which would otherwise have been rendered effective by the release of relay 4LAS.

Assuming now that the wayside circuits have been restored to their normal condition for traffic movements from right to left, as shown, and that the operator then transmits a code to station No. 1 to operate relay 2RHS to reverse, to clear signal 2RA or 2RB. This code will also cause the traffic relay 2RFS to close its right-hand contacts, and a second code will be transmitted to station No. 2, causing relay 4LFS to close its right-hand contacts, as already explained. Due to the reversal of relay 2RFS, relays 2LAR and 21HD, 21AR and 23HD, and 23AR and 4LHD all release, holding signals 21, 23, 4LA and 4LB at stop. Due to the reversal of relay 4LFS, terminals B and C of the source at station No. 2 are connected to the line circuit system at its right-hand end. The circuits for the two directions are similar, and it will therefore be evident without further description that relays 24HD, 22HD and 2RHD will become energized in cascade, in series with the approach relays 2RAR, 24AR and 22AR, respectively. Signals 24 and 22 will then be conditioned to indicate caution and proceed, respectively, and the block repeating relay 2BPR will become energized over circuits similar to those traced for relay 4BPR to release the approach locking relay 2RAS and thereby complete a circuit for mechanism 2RAG or 2RBG, depending upon the position of switch 1W, to cause signal 2RA or 2RB to clear.

It will be understood that as a train governed by any of the head block signals, signal 4LA for example, proceeds through the block, a directional stick relay 23S becomes energized in response to the release of the track relay 23TR, during the release period of relay 23HD, and when the block section in the rear of signal 23 is vacated, front contacts *a* and *b* of relay 23S connect terminals B and C to the line circuit system to energize relay 4LHD in the reverse direction whereby signal 4LA or 4LB may be conditioned to indicate caution. Similarly, relay 21S is energized upon the release of relay 21TR, during the release period of relay 21HD, whereby relay 23 may be conditioned to indicate caution to govern a following train, or if relay 2NWP is released, to permit relay 2WAR to be energized as required to permit a following train

to enter the block over switch 2W reversed, as hereinafter described.

Placing Fig. 2A at the right of Fig. 2B, it will be seen that relay 2LHD is normally energized with its polar contacts reversed over the circuit extending to terminals B and C at front contacts e and f of relay 4RAS and including contacts a and b of the track repeating relay 3TP, the pole changer contacts of relay 4LAPC, line wires 40 and 41 and front contacts of the track relay 6TR for the main track section. Relay 4LAPC is controlled by mechanism 4LAG and is energized to operate the polar contacts of relay 2LHD to their normal position when signal 4LA indicates caution or proceed.

When the signal control relay 2LHS is operated to reverse by code, with relays 1TP, 2LHD and 1NWP energized, the block repeating relay 2BPR at station No. 1 becomes energized over a circuit generally similar to that for relay 4BPR already described, and releases the approach locking relay 2LAS. When switch 1W is normal, the closing of back contact c of relay 2LAS completes a circuit for mechanism 2LAG, which extends from terminal B at the reverse contact a of relay 2LHS over front contact b of relay 2BPR, contacts c of relays 2RAS, 2TER and 2LAS, contacts c, e and f of relay 2LHD, contact b of relay 1NWP through mechanism 2LAG to terminal C at contact c of relay 2LHS, whereby mechanism 2LAG is energized to cause signal 2LA to indicate caution or proceed, depending on whether the polar contacts e and f of relay 2LHD occupy their reverse or normal position, respectively.

When switch 3W is reversed, the contacts of relays 4RAS and 3TP in the circuit for relay 2LHD are bridged by contacts e and f of relay 3RWP, in which case relay 2LHD may be energized to cause signal 2LA to indicate caution, for a movement up to signal 4LA, at stop, even though signal 4RB or 4LB has been cleared for a movement over switch 3W reversed.

When switch 1W is reversed, relay 2BPR may be energized by reversing the signal control relay 2LHS regardless of the condition of relay 2LHD, over the circuit extending from terminal B at the normal contact b of relay 2RHS, reverse contact b of relay 2LHS, front contact g of relay 2RWP, back contact a of relay 1NWP, front contact a of relay 1RWP, contact d of the track repeating relay 1TP through relay 2BPR to terminal C. Relay 2BPR when energized releases relay 2LAS, completing a circuit in this instance from terminal B at the reverse contact a of relay 2LHS over front contact b of relay 2BPR, contacts c of relays 2RAS, 1TER and 2LAS, contact b of relay 1RWP through mechanism 2LBG to terminal C at contact c of relay 2LHS, whereby mechanism 2RBG is energized to cause signal 2LB to indicate caution for a slow speed movement into the passing track.

Relay 4RHD, in Fig. 2B, is also normally energized with its polar contacts reversed, its circuit extending over line wires 42 and 43, to terminals B and C at front contacts of relays 2LAS or of relay 1RWP, and when relay 3NWP is energized the reversal of the signal control relay 4RHS causes relay 4BPR to become energized to release relay 4RAS and to cause signal 4RA to indicate caution or proceed by the operation of circuits similar to those for signal 2LA already described. Likewise, when switch 3W is reversed, relay 3RWP is energized and the re-

versal of relay 4RHS causes signal 4RB to indicate caution, its circuits being similar to those for signal 2LB as above described.

Outlying track switch control

The hand throw switch 2W, Fig 2B, is normally locked in its normal position as required for main track movements by the magnet 2WLM of an electric lock having a locking segment 25 mounted on a shaft carrying the contacts 47 and 49, the movement of which is limited by a locking dog on the magnet armature. Signals 22 and 23 which govern train movements over switch 2W are prevented from clearing except when the switch is locked normal by including contacts of the switch indication relay 2NWP in the line circuit as already described. Relay 2NWP is normally energized over a circuit which includes a contact N controlled by switch 2W which is closed only when the switch is locked normal, and also includes contact 49 which is closed only when the hand throw lever 8 is locked normal by the lock magnet 2WLM. Segment 25, and contacts 47 and 49 are also held normally in the position shown by the bail 50 of a padlock, which may be removed by the crew of a train after obtaining authority from the operator to unlock the switch. Segment 25 may then be moved a short distance to open the circuit including contact 49, releasing relay 2NWP, and to close contacts 46-47 in the circuit for magnet 2WLM.

For a train movement from the main track to the side track, magnet 2WLM will then become energized, provided the train has occupied the track section in approach to the switch, for a time sufficient to complete the operation of a time element relay TE controlled over back contacts e and f of the track relay 22TR, and the line wires 36 and 37.

For a train movement out of the side track, the central office operator will have cooperated by moving his switch lever 2WL to the left or right, according to the direction the train is to proceed after it enters the block, thereby initiating two control codes, one of which operates relay 2WLS to reverse and also operates relay 2RFS to the left or right to correspond with the position of lever 2WL, the other operating relay 4LFS to the right, so that terminals B and C become connected to the line circuit system at both ends, in lieu of at one end only. If the block is unoccupied, current is supplied over the line circuit system from both ends to energize the line relays 2WAR and 2EAR at the switch location, provided contact 49 has been opened to release relay 2NWP, and magnet 2WLM may then be energized over contacts 46-47. This permits segment 25 to be moved to its full reverse position, in which lever 8 is unlocked to permit switch 2W to be operated to reverse.

In the foregoing, it has been assumed that the block is unoccupied and that the system is in its normal condition as shown, in which case the master directional relay LP is free to respond to the switch lever operation so that either direction of traffic movement may be established. Switch 2W may also be unlocked while the block is occupied, provided the train therein has passed the switch location. In this case relay LP is held deenergized, retaining the established traffic direction, but one or the other of the two codes transmitted in response to the reversal of lever 2WL will be effective to energize the line circuit system at the station in the rear of the

train occupying the block, and when this train passes switch 2W, the release of relay 2NWP by the crew of the train on the side track will permit the energization of the corresponding one of the line relays 2WAR or 2EAR. The other of these relays will then become energized when the main line train vacates the block section containing switch 2W, by current supplied to its line circuit over front contacts of the directional stick relay 21S or 24S.

The code indication system

Each indication code is initiated by the release of a normally energized starting relay such as relay 1ST at station No. 1, which as shown by the circuits, occurs either in response to a change in the position of one or more of the indicating relays, or due to the momentary opening of contact *j* of the delivery relay 1D, when a control code is received. In each code initiated by relay 1ST, a selector relay 1S at the station is energized along with a delivery relay O1D in the corresponding office panel, in response to the station code call, to extend the indication channels 9-15 from the selected station to the corresponding office panel. At station No. 1, only channels 10, 12, 13, 14 and 15 are shown herein, over which the indication stick relays 1TK, 6TK, 2LHK, 2RBK, and 2RHK are energized in response to the closing of back contacts of the corresponding indicating relays 1TKS, 6TR, 2LGP, 2RBP and 2RGF at station No. 1. The release of the similar starting relay 3ST, at station No. 2, initiates a code in which a selector relay 3S and a delivery relay O3D are energized to control the indication stick relays 3TK, 4LBK, 4LHK and 4RHK over channels 10, 12, 13 and 15, and back contacts of relays 3TKS, 4LBP, 4LGP and 4RGF, respectively.

Relays 1TK and 3TK are the usual track indication relays which control the lamps 1TKE and 3TKE in the "OS" sections of the track diagram, and which also usually control pen magnets in a train graph as described in Patent No. 2,229,249. To prevent the loss of the indication of the arrival of a train at a station in the event the transmission of indications is delayed and the train vacates the controlling track section before an indication of its occupancy is transmitted, a storage relay such as relay 1TKS is provided.

When a train enters the detector track section 1T and releases the track relay 1TR, the opening of contact *a* of relay 1TR releases relay 1TKS, which relay by momentarily opening its contact *c* releases the starting relay 1ST to store the indication code for transmission as soon as the code line becomes available. Relay MSP is energized during the transmission of this code as described in Patent No. 2,229,249, and relay 1ST is reenergized during the eighth step, that is, during the step immediately preceding the series of steps during which the indication channels 9-15 are established. The contacts of relays MSP and 1ST in the pick-up circuit for relay 1TKS serve to hold this circuit open until the code is fully transmitted, thereby insuring the energization of the track indication relay 1TK over channel 10, even though the transmission of this code occurs after section 1T is vacated and relay 1TR is reenergized.

Relays 2RBK and 4LBK are block indication relays controlled from stations Nos. 1 and 2 over channels 14 and 12. Contacts *c* of these relays jointly control the block indication lamp BKE in the track diagram, which lamp is lighted to indicate the presence of a train in the block when

either relay 2RBK or 4LBK is energized by a received code, but not when these relays are energized locally by relay BKS, as already explained.

When the right-to-left direction is set up, relay 4LBP, the release of which initiates the transmission of an indication code for energizing relay 4LBK, is held energized, as shown in Fig. 2B, over the neutral contact *a* and the normal polar contact *d* of the signal relay 4LHD, only when the intermediate and right-hand block sections are both unoccupied, while relay 2RBP, the release of which initiates the transmission of an indication code for energizing relay 2RBK, is held energized, as shown, over contact *a* of the approach relay 2LAR, only when the left-hand block section is unoccupied.

When the left-to-right direction is established, relay 2RBP is energized over contacts *a* and *d* of relay 2RHD provided the left-hand and intermediate block sections are unoccupied, and relay 4LBP is energized over contact *a* of relay 4RAR, provided the right-hand block section is unoccupied.

A modification of this arrangement is required when the block contains more or less than three sections, as is obvious. Thus when the block contains more than three sections, line wire control may be employed to bridge the additional sections as disclosed in Fig. 2c of Letters Patent of the United States No. 2,344,333, issued March 14, 1944, to James J. Van Horn, for Railway Traffic Controlling Apparatus. When the block contains less than three sections, it is of advantage to transmit the block indications from one end of the block only, to reduce the number of indication codes transmitted, by omitting the circuits including contacts *a* of the approach relays, as disclosed in a pending application for Letters Patent of the United States, Serial No. 567,188, filed December 8, 1944, by Frank T. Pascoe and Arthur L. Jerome, for Railway Traffic Controlling Apparatus, which issued as Patent No. 2,411,387, on November 19, 1946. In this arrangement, the relay 2RBK or 4LBK for the exit end of the block is energized regardless of traffic conditions because the signal relay which controls it is released, requiring a change in the connection of the front contacts *b* and *c* of these relays from parallel to series, and of their back contacts *b* from series to parallel, as illustrated in Figs. 2 and 3 of the application referred to, in order to enable the circuits controlled by these contacts to function in the normal manner, as hereinbefore described.

Lamp BKE is also lighted upon the reception of the return indication code which follows the switch lock control codes initiated by the reversal of the switch lock lever 2WL, as already mentioned. One of these control codes reverses relay 2WLS and the other reverses relay 4LFS. The opening of contact *c* of relay 2WLS releases relay 2RBP, thereby initiating an indication code by which relay 2RBK is energized, which suffices to light lamp BKE when the contacts *c* of relays 2RBK and 4LBK are connected in parallel as shown, as is obvious. In the case of the short block mentioned, where these contacts are connected in series, lamp BKE will also be lighted in response to the reversal of lever 2WL, due to the energization of both block indication relays.

The signal indication relays 2RHK and 2LHK control a red lamp 2NE and green lamps 2LE and 2RE associated with lever 2SG, as shown in Fig. 1, and the relays 4RHK and 4LHK control the lamps 4LE, 4NE and 4RE associated with

lever 4SG, by similar circuits, not shown. The signal indication relays are controlled over channels 13 and 15, and by reference to Fig. 2A it will be seen that normally, the signals at station No. 1 are at stop and their indication relays 2LGP and 2RGP and the approach locking relays 2LAS and 2RAS are all energized, in which case channels 13 and 15 are not energized and relays 2LHK and 2RHK assume their released position in response to the operation of relay O1D, thereby completing a circuit over their back contacts *d* to light the red lamp 2NE.

If now relay 2RHS or 2LHS is reversed by a control code, energizing relay 2BPR and thereby releasing relay 2RAS or 2LAS, and if due to a fault, the signal fails to clear so that relays 2RGP and 2LGP remain energized, terminal B at back contact *g* of relay 2LAS or 2RAS is connected over front contacts *a* of relays 2RGP and 2LGP to channels 13 and 15, and relay 1ST is released by the momentary opening of contact *h* of relay 2RAS or 2LAS to initiate an indication code whereby relays 2RHK and 2LHK are both energized. Lamp 2NE is thereby connected over front contacts *c* of relays 2LHS and 2RHS to a source of coded or interrupted current identified by the reference character CB, and is so caused to display a flashing indication indicating the approach locked condition. If one of the signals governed by the operated control relay 2RHS or 2LHS assumes its energized position, the corresponding indication relay 2RGP or 2LGP releases and by opening its contact *c* initiates a second code. If signal 2RA or 2RB clears, relay 2RGP releases and its contact *a* disconnects terminal B from channel 13 but not from channel 15, and in response to the code, relay 2LHK is released and relay 2RHK is held energized, to extinguish lamp 2NE and light lamp 2RE over front contact *d* of relay 2RHK and back contact *e* of relay 2LHK. Similarly, if signal 2LA or 2LB clears, relay 2LGP releases to disconnect terminal B from channel 15 but not from channel 13, so that relay 2LHK is energized and relay 2RHK released to light lamp 2LE.

When a cleared signal is restored to stop, energizing relay 2RGP or 2LGP, the approach locked indication code by which both relays 2RHK and 2LHK are energized will be transmitted in lieu of the stop indication code by which both these relays are released, if either relay 2RAS or 2LAS remains released, as will be readily apparent.

Operation

I shall first assume that the system is in its normal condition as shown, with lamp LFE lighted to indicate that the right-to-left traffic direction is set up but with signals 4LA and 4LB at stop, and shall trace the operations for clearing signals 2RA and 4RA for a train movement from left-to-right.

The operator moves lever 2SG to the right, which completes a circuit from terminal B at back contact *b* of relay 2RBK over back contacts *b* of relays 4LBK, 1TK, 3TK, 2RM and 4LM, the right-hand contact *b* of signal lever 2SG, the normal or right-hand contact *a* of lever 4SG, left-hand contact *b* of relay LP, back contact *a* and winding of relay LPS to terminal C at back contact *e* of relay 2WLP. Relay LPS picks up and completes a stick circuit at its own front contact *a* extending to terminal B at back contacts *c* of relays O1ST and O3ST.

The operator then presses button 1STB, en-

ergizing relay O1ST over the button contact *a*, and energizing relay O3ST over the circuit from terminal B at the right-hand contact *f* of lever 2SG, contact *b* of button 1STB, contact *h* of relay 2LPS, through relay O3ST to terminal C, also energizing relay BKS over the circuit extending from terminal B at contact *c* of button 1STB, contact *f* of relay LPS through relay BKS to terminal C at back contact *f* of relay 2WLP, and 10 energizing the relay LP over the circuit including contacts *b* of the indication and signal clearing relays 2RBK, 4LBK, 1TK, 3TK, 2RM and 4LM and of lever 2SG, contact *a* of lever 4SG, contact *d* of button 1STB, and contact *b* of relay LPS, 15 through the upper winding of relay LP to terminal C, whereby relay LP is operated to close its right-hand contacts.

The starting relays O1ST and O3ST are held energized over back contacts *i* of the corresponding selector relays O1S and O3S and open the stick circuit for relay LPS, which relay therefore releases after a brief period but without re-establishing its pick-up circuit, due to the opening of left-hand contact *b* of relay LP. Before 25 relay LPS releases, circuits are completed momentarily over contacts *d* and *e* of relays BKS and LPS to pick up the block indication relays 2RBK and 4LBK, which relays thus assume positions corresponding to the occupied block condition and are held energized over their stick circuits including their own front contacts *a* and the back contacts *f* and *d* of the delivery relays O1D and O3D, respectively, and by closing their front contacts *b*, complete a stick circuit 30 for relay BKS including back contacts *d* of relays 1TK and 3TK and front contact *a* of relay BKS for holding relay BKS energized. The opening of back contact *c* of relay BKS extinguishes lamp LFE and maintains lamps RFE and 35 BKE dark, while the closing of front contact *b* of relay BKS prepares a circuit for the lower winding of relay LP which is open at contact *c* of relay LPS, while the circuit for the upper winding of relay LP as traced above is now open at contact *b* of relay LPS.

45 The closing of contacts *c* of relays O1ST and O3ST initiates the transmission of control codes to the corresponding stations Nos. 1 and 2 at the opposite ends of the block, as described in Patent No. 2,229,249. In the code initiated by relay O1ST, relays O1S and 1D are operated, and as soon as relay O1S picks up, relay 2RM is energized over the circuit from terminal B at front contact *h* of relay OM, contacts *d* of relays 2WLP, LP and O1S, contact *c* of lever 2SG, back contact *b* of relay 2LG through relay 2RM to terminal C at back contact *e* of relay 1TK. Relay 2RM picks up and completes a stick circuit extending to terminal B at back contact *b* of relay 2-4Z and opens its back contacts *b*, *d* and *e* to lock relays LP and LPS, 2WLP and 2LG de-energized. Relays O1S connects terminal B to channel 7 only, in this instance, and since the connection from contact *c* of relay LP to channel 2 over contact *e* of relay O1S is now open, relay 1F2, Fig. 2A, is not operated and relay 2RFS is operated to close its right-hand contacts *a* and *b*, by relay 1D. Channel 4 is open, so that relay 2WLS is operated to the left, but channel 7 is energized over contact *g* of relay O1S, contact *d* of lever 2SG, contacts *e* of relays 2RM and 2-4Z, and contact *c* of relay LP, so that relay 1F1 is energized and relay 2RHS is operated to the right. In the code initiated by relay O3ST, relays O3S and 3D are operated, en-

ergizing channel 2 only, over contact *c* of relay LP, back contact *k* of relay LPS, and contact *e* of relay O3S, to operate relays 4LFS to the right.

It may be that the operator will have also operated lever 4SG to the right, with the intention of clearing signal 4RA or 4RB, but without operating button 3STB because at the time he is uncertain which of these signals he wishes to clear. The reversal of lever 4SG is without effect upon the code transmitted to station No. 2 by the operation of button 1STB as above described, because relay 4RG has not been energized. The operator may however render this code effective to clear signal 4RA or 4RB by pressing button 3STB before it is transmitted, to pick up relay 4RG over contacts *e* of lever 4SG and of button 3STB, in which case channel 7 will be energized over contact *c* of relay 4RG and relay 4RHS will be operated to reverse by the code by which relay 4RFS is operated.

Relays 2RFS and 4LFS in their right-hand positions reverse the direction of energization of the line circuit system as hereinbefore described. Relay 4LBP is picked up by relay 4RAR, and relay 2RBP by relay 2RHD, and since the right-hand contacts of relay 2RHS are closed, relay 2BPR is energized by relay 2RHD when the energization of the line circuit system is completed, releasing relay 2RAS and thereby energizing mechanism 2RAG to clear signal 2RA, the energization of mechanism 2RAG causing relay 2RGP to release.

These operations result in the initiation of one or more indication codes from each station, whereby relays 2RBK and 4LBK are released, thereby releasing relay BKS and lighting lamp RFE to indicate the traffic direction established, and relay 2RHK becomes energized, lighting lamp 2RE to indicate the clearing of signal 2RA or 2RB.

Usually these codes will all be transmitted before the train governed by signal 2RA enters the block, but if the code system controls a large number of stations and the traffic is heavy, it may happen that the train will pass signal 2RA at clear and enter the block before the system has an opportunity to transmit the indication code by which relay 2RHK is energized and relay 2RBK released. In this case, the first code received from station No. 1, following the transmission of the control codes for reversing the traffic direction, will be the "OS" code, energizing relay 1TK, even though the train has vacated the detector section before this code is transmitted, due to its storage by relay 1TKS. The opening of contact *e* of relay 1TK releases relay 2RM, but the opening of contact *b* of relay 1TK now holds relays LP and LPS deenergized, and the opening of contact *d* of relay 1TK releases relay BKS, rendering relay 2RBK effective, provided it is maintained energized by this code, to light lamp BKE to indicate the occupied block indication. Due to the release of relay BKS by relay 1TK, relays 2RBK and 4LBK are rendered effective to maintain relays LP and LPS deenergized, after relay 1TK is released, by a code transmitted from station No. 1 to indicate that the train has vacated the detector section. Lamp RFE also becomes lighted to indicate the established direction of traffic as in the preceding example.

It will be seen that lamp BKE indicates whether or not the block is occupied only when lamp RFE or LFE is lighted to indicate that the corresponding direction of traffic is established,

and that while the traffic direction is being established all three lamps are dark.

The operator may wish to repeat the control operations above described, in the event the transmission of the code indicating the clearing of signal 2RA or 2RB is delayed, and will re-operate the starting button 1STB. This will result in the transmission of a code to station No. 1 only, since relay LPS will not be operated. This code being a repetition of that previously transmitted, will merely maintain relays 2RFS and 2RHS reversed, provided it is received before the train enters the detector section 1T. When the train enters section 1T, relay 1TR is released and relay 2RHS is operated to normal by the momentary energization of its lower winding over contacts *f* of relays 1TR and 1TKS. Relay 1TR releases relay 1TKS, as already explained, and contact *e* of relay 1TKS disconnects the upper winding of relay 2RHS from the pole changer contacts *a* and *b* of relay 1F7 and connects it to back contact *c* of that relay. Relay 2RHS is thus rendered non-responsive to a signal clearing code received while relay 1TKS is released and so remains in its normal position if this code is repeated after the train enters the detector section but before the "OS" indication has been transmitted by which the signal clearing relay 2RM is released.

Assuming that the train has vacated section 1T when the track occupied code is transmitted, relay 1ST becomes reenergized, and relay 1TKS picks up, whereupon relay 1ST releases again to store a track unoccupied code for transmission. Relay 2RHS is now in condition to respond to the energization of channel 7, but since the indication relay 1TK is energized, relay 2RM is held released, preventing the energization of channel 7 in a code transmitted to station No. 1. It follows that signal 2RA or 2RB may be cleared for a following train only by operating button 1STB after an indication is received that the first train has vacated section 1T.

It may be that the operator after having initiated the reversal of traffic as above described will wish to restore the original traffic direction, due to a change in orders or in case it is found that the reverse direction cannot be set up due to a fault. It has already been pointed out that the block indication relays 2RBK and 4LBK are incapable of indicating block conditions at this time and are held energized locally, relay BKS having been energized to prepare circuits for relays LPS and LP, but these circuits are now held open at back contact *b* of relay 2RM. The operator will therefore take steps leading to the release of relay 2RM, in order to unlock the traffic direction apparatus, by restoring lever 2SG to its normal position and pressing button 1STB, to cause the transmission of a signal stop code for restoring relay 2RHS to normal. On the eighth step of this code, relay 2-4Z is picked up over back contact *a* of relay M8P, contact *c* of relay O1S, contact *g* of lever 2SG, and contact *e* of relay 2RM, completing a stick circuit at its own front contact *a*, and extending the stick circuit for relay 2RM over front contact *b* of relay 2-4Z to terminal B at back contact *h* of relay O1D.

Channel 7 is open at contact *d* of lever 2SG and at contact *e* of relay 2-4Z, and when the delivery relay 1D is operated by this code, relay 2RHS is operated to normal, and relay 1ST is released to initiate a return indication code.

Assuming first that the traffic reversal had not been completed and that the approach locking relays **2RAS** and **2LAS** are both energized so that channels **13** and **15** are open. When the delivery relay **O1D** is operated by this indication code, relays **2LHK** and **2RHK** remain released to maintain lamp **2NE** lighted and since channel **15** is open, relay **2RM** is released by the operation of contact **h** of relay **O1D**, and relay **2-4Z** is then released by the opening of contact **e** of relay **2RM**. The fact that relay **2RAS** is found to be in its energized condition manifests that signal **2RA** or **2RB** has not been cleared.

Assuming now that the operations involved in reversing traffic had progressed further before this signal stop code is transmitted and that relay **2RAS** has been released, the operation of relay **2RHS** to normal by the code will restore signal **2RA** or **2RB** to stop, if it has been cleared, re-energizing relay **2RG** and completing a circuit over back contact **a** of relay **2RAS** for the time element relay **1TER** by means of which relay **2RAS** is reenergized after a predetermined time interval. Channels **13** and **15** are both supplied with current over back contact **g** of relay **2RAS**, and when relay **O1D** is operated by the return indication code, relays **2RHK** and **2LHK** are picked up to cause lamp **2NE** to display a flashing indication, to indicate the approach locked condition, and relay **2RM** will remain energized, being connected to terminal **B** over channel **15** while back contact **h** of relay **O1D** is open. At the end of the time delay period, relay **2RAS** is picked up by relay **1TER** and initiates a second indication code to release relays **2RHK**, **2LHK** and to also release relay **2RM** to condition relay **LPS** for operation as in the preceding examples.

In each of the foregoing examples, the unoccupied block indication stored by relay **BKS** corresponds to the actual conditions, making it proper to reverse traffic as soon as relay **2RM** is released, provided relay **BKS** remains energized. It may be however, due to an extended delay in the transmission of indication codes, that the train will have entered the block and will be approaching one of the intermediate signals at clear, at the time the operator decides to reestablish his control of the traffic direction apparatus by the transmission of a signal stop control code for restoring the signal control relay **2RHS** to normal. In this case the signal stop code finds relay **2RHS** already restored to normal, with relay **2RAS** reenergized, by relay **1TR**. The next indication code received from station No. 1 will include the stored "OS" indication by which relay **1TK** is energized over channel **10**, channels **13** and **15** being open. This indication code will release relays **2RM** and **2-4Z** as in the preceding examples and for the additional reason that contact **e** of relay **1TK** is opened, but at the same time contact **b** of relay **1TK** opens to hold relay **LPS** deenergized, and relay **BKS** is released by the opening of contact **d** of relay **1TK**, while relays **2RBK** and **4LBK** remain energized to hold relay **LPS** deenergized until indications that the entire block is vacated are received. It will be clear therefore, that relay **BKS** ceases to be effective when relay **2RM** is released by an "OS" code, and that the operator is enabled to regain control of the traffic direction apparatus only when relay **2RM** is released by an indication code which indicates that the block has not been entered. One important advantage of this arrangement is that it prevents the operator from inadvertently causing an intermediate signal to be put to stop

in front of a train, the presence of which in the block has not been indicated at the office.

I shall now trace the operations involved in unlocking switch **2W**, assuming that the right-to-left traffic direction is set as shown, and also assuming that the crew of a train on the siding at switch **2W** has communicated with the operator by telephone, requesting authority to enter the block and to move their train in the opposite direction, that is toward the right.

The operator moves lever **2WL** to its right-hand position, leaving the signal levers **2SG** and **4SG** both in their normal positions, as shown. Contacts **a** and **b** of lever **2WL** close momentarily, energizing the starting relays **O1ST** and **03ST** to initiate the transmission of control codes to stations at both ends of the block. The closing of right-hand contact **d** of lever **2WL** completes a circuit from terminal **B** over back contacts **d** of relays **2RM** and **4LM** to energize relay **2WLP**, which by closing its contact **c** completes a circuit from terminal **B** over back contacts **b** of relays **2RBK**, **4LBK**, **1TK**, **3TK**, **2RM** and **4LM**, contacts **c** of relay **2WLP** and of lever **2WL** through the upper winding of relay **LP** to terminal **C**, so that relay **LP** is operated to its right-hand position to correspond with the position of lever **2WL**. Relays **LPS** and **BKS** are now locked released by the opening of back contacts **e** and **f** of relay **2WLP**, and relays **2RM** and **4LM** by the opening of back contact **d** of relay **2WLP**.

It may be assumed that levers **2SG** and **4SG** will be left in their normal positions, but this is not essential, since channels **5** and **7** will be held open and relay **LPS** will remain released even though the signal levers are displaced from normal, because the circuits for relays **2RM**, **4LM**, **LPS** and **BKS** are held open by relay **2WLP**, and the energization of relays **2LG** and **4RG** requires the combined operation of the signal lever and the associated starting button. The inadvertent reversal of a signal lever therefore has no effect upon the control codes initiated by the reversal of the switch lock lever **2WL**.

In the code transmitted to station No. 1, channel **2** is not energized, but channel **4** is energized over contact **b** of relay **2WLP**, and in the code transmitted to station No. 2, channel **2** is energized over contact **a** of relay **2WLP** and also over the right-hand contact **c** of relay **LP**. Consequently these codes serve to operate each of the relays **2WLS**, **2RFS** and **4LFS** to the right, in which case, as will be clear from Figs. 2A and 2B, the line circuit system is supplied with current at both ends.

In Fig. 2A, terminals **B** and **C** are now connected to the line circuit for relay **21HD** over the right-hand contacts **a** and **b** of relays **2WLS** and **2RFS** instead of over the left-hand contacts of relay **2RFS** so that relays **2LAR** and **21HD** remain energized, likewise relay **23HD**, but relay **4LHD** is released by relay **4LFS** so that signals **21** and **23** remain in condition to indicate caution and proceed, respectively, but the head block signals are all held at stop. The opening of contact **c** of relay **2WLS** releases relay **2RBP**, initiating an indication code by which relay **2RBK** is energized to lock relay **LP** deenergized and to light lamp **BKE**. Lamp **LFE** is extinguished and lamp **RFE** lighted in response to the operation of relay **LP** by the switch lever, because relay **BKS** is not operated.

When the switch lock segment is operated by 75 the train crew to its intermediate position relay

2NWP releases, thereby releasing relay 23HD to condition signal 23 to indicate stop and relay 2WAR becomes energized. The release of relay 23HD allows relay 24HD to become energized in series with relay 4RAR to condition signal 24 to indicate caution and to supply current to the line circuit section in the rear thereof to energize relay 2EAR. Relays 2WAR and 2EAR when energized complete a circuit over contacts 46-47 for the lock magnet 2WLM to permit switch 2W to be unlocked.

Segment 25 is then operated to its full reverse position to unlock lever 8, and the switch is reversed by the operation of lever 8 to permit the train to enter the main track and to release relays 23TR and 22TR which in turn release relays 2EAR and 2WAR. The train crew then locks switch 2W normal, relay 2NWP becoming reenergized.

The operator when advised that the switch is locked normal, may restore lever 2WL to its normal center position. This again closes contacts *a* and *b* of lever 2WL momentarily to initiate the transmission of codes to both ends of the block. Relay 2WLP is released by the opening of contact *d* of lever 2WL, and it follows that in response to these codes relay 2WLS is operated to the left, relays 2RFS and 4LFS remaining in their right-hand positions. Relays 2LAR and 2HD release, relay 2RBP remains released and maintains relay 2RBK energized, so that lamp BKE remains lighted, indicating the occupancy of the block. The release of relay 2HD restores signal 23 to stop. As the train passes signal 24 at caution, relays 24TR, 24HD, 4RAR and 4LBP release and the directional stick relay 24S becomes energized, and an indication code is initiated by relay 4LBP by which the block indication relay 4LBK is energized.

It will be noted that if lever 2SG is moved to the right prior to the restoration of lever 2WL to normal, the code initiated by the operation of lever 2WL which is transmitted to station No. 1 will be effective to reverse relay 2RHS, but the code transmitted to station No. 2 will be effective to reverse relay 4RHS only if button 2STB is operated while lever 4SG occupies its right-hand position, in order to pick up relay 4RG.

Since relay 24S has been picked up, it follows that when the train vacates the intermediate block section, relay 22HD becomes energized in the reverse direction, energizing relay 2RHD in the normal direction, thereby energizing relay 2RBP which initiates a code by which relay 2RBK is released, but lamp BKE remains lighted due to the energization of relay 4LBK, until the train vacates the block. Signal 22 is conditioned to indicate caution, and if relay 2RHS has been reversed, the energization of relay 2RHD causes signal 2RA or 2RB to be conditioned to indicate proceed to permit a following train to enter the block.

Assuming next that with the right-to-left traffic direction set up as shown, that the switch 2W is to be unlocked to permit a train to enter the block and to move in the established direction, toward the left. In this case the operator moves lever 2WL to the left, energizing relay 2WLP and the lower winding of relay LP, holding relay LP in its left-hand position, and initiating codes by which relays 2WLS and 4LFS are operated to the right by relay 2WLP, and relay 2RFS is held in its left-hand position by relay LP, energizing the line circuit system at both ends so that switch 2W may be unlocked, as in the preceding example.

Since in this instance the traffic direction is not changed, these operations may be carried out while the block is occupied by a preceding train, provided it has vacated the block section containing switch 2W. Thus if the left-hand section is occupied by a train moving toward the left, the directional stick relay 24S will be energized in lieu of relay 2HD, to supply current to relay 2WAR in response to the release of relay 2NWP, the operations in other respects being similar to those already described.

Although I have herein shown and described only one form of apparatus embodying my invention, it is understood that various changes and modifications may be made therein within the scope of the appended claims without departing from the spirit and scope of my invention.

Having thus described my invention, what I claim is:

1. Railway traffic controlling apparatus for governing traffic movements in a stretch of single track railway equipped with a reversible signaling system having an entering signal at each end controllable by a signal control relay in accordance with traffic conditions in the stretch when the corresponding traffic direction is established, comprising a directional relay for designating the direction of traffic movement, a signal lever and a signal clearing relay for each signal all located at a control office, a code type communication system for transmitting control codes to the signal locations to operate the signal control relays and for transmitting indication codes to the office for indicating traffic conditions in the stretch, means for operating said directional relay in response to the reversal of either signal lever to a position designating the corresponding traffic direction provided said signal clearing relays are deenergized and the unoccupied block condition is indicated by said code system, means acting when a control code is transmitted with either signal lever reversed for energizing the associated signal clearing relay, means rendering such code effective to operate the corresponding signal control relay to effect the clearing of its signal only if such signal clearing relay is energized, and means for maintaining such signal clearing relay energized until an indication code is received which indicates that the operated signal control relay has been restored to its normal position.

2. Railway traffic controlling apparatus located at a central office for controlling traffic in a stretch of single track railway equipped with an entering signal at each end governed from said office by a signal control relay and also governed in accordance with traffic conditions in said stretch, a signal lever and a signal clearing relay controlled thereby for each signal, a two position directional relay for designating the direction of traffic movement in said stretch, a code type communication system having a starting relay for each signal lever, a starting button for each signal lever effective when operated to actuate its starting relay to thereby initiate the transmission of a code reflecting the position of the associated signal lever and of its signal clearing relay and also that of said directional relay, to which code the signal clearing relay at the corresponding end of the stretch is responsive, a track indication relay for each end of the stretch arranged to be energized when a train enters the stretch at the corresponding end, a normally deenergized direction locking relay, a circuit for energizing said direction locking relay closed upon the operation

of one signal lever or the other to its signal clearing position including back contacts of both signal clearing relays and of both track indication relays and also including a contact of the directional relay closed only when a reversal of traffic direction is required in order to clear the signal controlled by the operated lever, circuits closed by the operation of the starting button for such lever when the direction locking relay is energized for operating the directional relay to the position designating the corresponding traffic direction and for then releasing said direction locking relay, a circuit closed upon the initiation of a code by the starting relay which such button controls for energizing the signal clearing relay associated with the operated signal lever, and a circuit for maintaining such signal clearing relay energized only until the track indication relay for the corresponding end of the stretch becomes energized.

3. Railway traffic controlling apparatus located at a central office for controlling traffic in a stretch of single track railway equipped with an entering signal at each end governed by a signal control relay and also governed in accordance with traffic conditions in the stretch, a code type communication system connecting said office with stations at the ends of the stretch, said apparatus comprising a two position directional relay, a signal lever and a signal clearing relay for each signal, a starting button for each lever effective when operated to actuate a starting relay associated therewith to initiate the transmission of a code by said communication system reflecting the positions of the associated signal lever and of its signal clearing relay to which the signal control relays at the corresponding end of the stretch are responsive, means controlled by the signals for indicating their condition and that of their control relays, indication relays controlled by traffic conditions for indicating when the stretch is unoccupied, a normally de-energized direction locking relay, a circuit for energizing said direction locking relay closed upon the operation of one signal lever or the other to its signal clearing position including back contacts of the signal clearing relays and contacts of said indication relays which when closed indicate that the stretch is unoccupied, and also including a contact of the directional relay closed only when a change in the traffic direction indicated by such relay is required in order to clear the signal controlled by the operated lever, circuits closed by the operation of the starting button for the operated lever when the direction locking relay is energized for operating said directional relay to the position required to establish the corresponding direction and for actuating the starting relays associated with both signal levers, a circuit for maintaining said direction locking relay energized after the directional relay is operated only until both starting relays are actuated, a circuit controlled by said directional relay for energizing the signal clearing relay for the operated signal lever in response to the initiation of a code by the associated starting relay, and means for maintaining such signal clearing relay energized only until indications are received which manifest that the signal control relay governed by such code has been restored to its normal position.

4. Direction selecting apparatus for controlling traffic movements over a stretch of single track railway equipped with a reversible signaling system having an entering signal at each end pro-

vided with a control relay for governing its operation in accordance with traffic conditions in the stretch when the signaling system is set up in the corresponding direction and also having a two position directional relay for designating the direction of traffic movement, a code type communication system for transmitting manually initiated control codes to stations at the ends of the stretch to operate the control relay at the entering end designated by said directional relay and to energize said signaling system at its opposite end as required for the clearing of the entering end signal, and for also transmitting indication codes from said stations to report the condition of said signals and of their control relays, a manually controllable signal clearing relay, circuit means requiring said signal clearing relay to be energized to render a control code transmitted to the station at the entering end of the stretch effective to operate the control relay thereat to its signal clearing position, means for energizing said signal clearing relay when such code is initiated, and means controlled by said signal clearing relay for preventing a change in the position of said directional relay from the time said signal clearing relay becomes energized until the operated signal control relay is returned to normal and the signal governed thereby is returned to its stop position and its return is reported by an indication code transmitted by said code system.

5. Direction selecting apparatus for controlling traffic movements over a stretch of single track railway equipped with a reversible signaling system having an entering signal at each end provided with a control relay for governing its operation in accordance with traffic conditions in the stretch when the signaling system is set up in the corresponding direction and also having a two position directional relay for designating the direction of traffic movement, an approach locking relay for each signal which when energized manifests that the signal is at stop and that its control relay is in a normal position, a code type communication system for transmitting manually initiated control codes to stations at the ends of the stretch to operate the control relay at the entering end designated by said directional relay and to energize said signaling system at its opposite end, provided the approach locking relay thereat is energized, to effect the clearing of the entering end signal, and for also transmitting indication codes from said stations to report the condition of said approach locking relays, a manually controllable signal clearing relay, circuit means requiring said signal clearing relay to be energized to render a control code transmitted to the station at the entering end of the stretch effective to operate the control relay thereat to its signal clearing position, means for energizing said signal clearing relay when such code is initiated, and means controlled by said signal clearing relay for preventing a change in the position of said directional relay from the time such control code is initiated until the re-energization of the approach locking relay at the entering end is reported by an indication code transmitted by said code system.

6. Direction selecting apparatus for controlling traffic movements over a stretch of single track railway equipped with a reversible signaling system having an entering signal at each end provided with a control relay for governing its operation in accordance with traffic conditions in the stretch when the signaling system is set up in

the corresponding direction and also having a two position directional relay for designating the direction of traffic movement, an approach locking relay for each signal which when energized manifests that the signal is at stop and that its control relay is in a normal position, a code type communication system for transmitting manually initiated control codes to stations at the ends of the stretch to operate the control relay at the entering end designated by said directional relay and to energize said signaling system at its opposite end, provided the approach locking relay thereat is energized, to effect the clearing of the entering end signal, and for also transmitting indication codes from said stations to report the condition of said approach locking relays, a manually controllable signal clearing relay for each direction, means for energizing the signal clearing relay for the direction designated by said directional relay when the transmission of a code to the station at the entering end for such direction for clearing the signal at such station is initiated, means controlled by such signal clearing relay when energized for rendering such code effective to operate the signal control relay at such entering end to its signal clearing position and to prevent a change in the position of said directional relay, and means for maintaining such signal clearing relay energized in the event the stretch is not entered by a train, until the re-energization of the approach locking relay released in response to such code has been effected by the transmission of a second control code for restoring the cleared signal manually to stop, and the reenergization of such relay is reported by an indication code transmitted by said code system.

7. In combination with a stretch of single track railway having an entering signal at each end governed by traffic conditions in the stretch and by a signal control relay controlled by a signal lever at a central office, a code system for transmitting manually initiated control codes to operate said control relays in accordance with the positions of said levers and for transmitting indication codes to operate indication relays at the office reflecting the condition of occupancy of the stretch and the condition of the signals and of their control relays, a two position directional relay for designating the direction of traffic movements, a signal clearing relay for each signal, circuits closed in response to the operation of either signal lever when the other signal lever is normal for operating said directional relay to a position designating the direction of traffic governed by the operated lever, said circuits including back contacts of both signal clearing relays and contacts of said indication relays which when closed indicate that the stretch is unoccupied, means rendering a control code governed by the operated lever effective to operate the signal control relay which such code controls to its signal clearing position only if transmitted when the associated signal clearing relay is energized, means controlled by the directional relay in the position designating the corresponding traffic direction for energizing such signal clearing relay upon the initiation of such code, means for maintaining such signal clearing relay energized following the transmission of said control code either until an indication code is received indicating that a train governed by the signal cleared in response to such code has entered the stretch, or an indication code is received indicating that the signal has been manually restored to stop by the transmission

of a second control code, and means for automatically restoring said signal control relay to its normal position when said train enters the stretch.

5 8. In combination with a stretch of single track railway having an entering signal at each end governed by traffic conditions in the stretch and by a signal control relay controlled by a signal lever at a central office, a code system for transmitting manually initiated control codes to operate said control relays in accordance with the positions of said levers and for transmitting indication codes to operate indication relays at the office reflecting the condition of occupancy of the stretch and the condition of the signals and of their control relays, a two position directional relay for designating the direction of traffic movements, a signal clearing relay for each signal, circuits closed in response to the operation of either 10 signal lever when the other signal lever is normal for operating said directional relay to a position designating the direction of traffic governed by the operated lever, said circuits including back contacts of both signal clearing relays and contacts of said indication relays which when closed indicate that the stretch is unoccupied, means rendering a control code governed by the operated lever effective to operate the signal control relay which such code controls to its signal clearing 15 position only if transmitted when the associated signal clearing relay is energized, means controlled by the directional relay in the position designating the corresponding traffic direction for energizing such signal clearing relay upon the initiation of such code, and means for maintaining such signal clearing relay energized following the transmission of said control code until an indication code is received indicating that either a train governed by said signal has entered the 20 stretch or that the signal cleared in response to said code has been restored to stop and that its control relay occupies its normal position.

9. In combination with a stretch of single track railway having an entering signal at each end governed by traffic conditions in the stretch and by a signal control relay controlled by a signal lever at a central office, a code system for transmitting manually initiated control codes to operate said control relays in accordance with the positions of said levers and for transmitting indication codes to operate indication relays at the office reflecting the condition of occupancy of the stretch and the condition of the signals and of their control relays, a two position directional relay for designating the direction of traffic movements, a signal clearing relay for each signal, circuits closed in response to the operation of either signal lever when the other signal lever is normal for operating said directional relay to a position designating the direction of traffic governed by the operated lever, said circuits including back contacts of both signal clearing relays and contacts of said indication relays which when closed indicate that the stretch is unoccupied, means rendering a control code governed by the operated lever effective to operate the signal control relay which such code controls to its signal clearing position only if transmitted when the associated signal clearing relay is energized, means controlled by the directional relay in the position designating the corresponding traffic direction for energizing such signal clearing relay upon the initiation of such code, a stick circuit for maintaining such signal clearing relay energized following the transmission of such control

code, means for automatically restoring said signal control relay to normal when a train governed by the signal cleared by such control code enters the stretch, and means responsive to an indication code indicating that a train governed by the signal cleared by such code has entered the stretch for opening said stick circuit.

10. In combination with a stretch of single track railway having an entering signal at each end governed by traffic conditions in the stretch and by a signal control relay controlled by a signal lever at a central office, a code system for transmitting manually initiated control codes to operate said control relays in accordance with the positions of said levers and for transmitting indication codes to operate indication relays at the office reflecting the condition of occupancy of the stretch and the condition of the signals and of their control relays, a two position directional relay for designating the direction of traffic movements, a signal clearing relay for each signal, circuits closed in response to the operation of either signal lever when the other signal lever is normal for operating said directional relay to a position designating the direction of traffic governed by the operated lever, said circuits including back contacts of both signal clearing relays and contacts of said indication relays which when closed indicate that the stretch is unoccupied, means rendering a control code governed by the operated lever effective to operate the signal control relay which such code controls to its signal clearing position only if transmitted when the associated signal clearing relay is energized, means controlled by the directional relay in the position designating the corresponding traffic direction for energizing such signal clearing relay upon the initiation of such code, a stick circuit for maintaining such signal clearing relay energized following the transmission of such control code, a release relay, means for energizing said relay upon the transmission of a control code if said signal clearing relay is energized but the associated signal lever has been restored to normal to render such code effective to restore the cleared signal manually to stop, means for maintaining said release relay energized only as long as said signal clearing relay is energized and said signal lever remains in its normal position, means controlled by an indication code which indicates the occupancy of said stretch for opening the stick circuit for the energized signal clearing relay, and means controlled by an indication code received when said release relay is energized which does not indicate the occupancy of said stretch for opening the stick circuit for the energized signal clearing relay only if such indication code indicates that the corresponding signal has been restored to stop and that its control relay is in its normal position.

11. In combination with a stretch of single track railway equipped with a reversible signaling system controlled by traffic conditions in the stretch, an entering signal at each end of the stretch controllable by said signaling system and by a signal control relay, a hand throw switch in said stretch having an electric lock, manually operable means for energizing said lock to unlock said switch, said means being rendered effective when said signaling system is divided into two portions which extend from the switch location to the two ends of the stretch and said portions are set up for movement in opposite directions away from the switch location, and jointly indicate at such location that the entire stretch is unoccu-

pied, a signal lever and a signal clearing relay for each signal, and a switch lever for the switch, a code system for transmitting control codes to the ends of the blocks to govern said signaling system and said signal control relays, a starting button for each signal lever effective when such lever is reversed to cause the energization of the associated signal clearing relay and the transmission of codes by which the signal control relay for the signal which such lever controls is operated to its signal clearing position and said signaling system is set up in the direction for clearing such signal, means responsive to the operation of said switch lever for preventing the energization of either signal clearing relay and for causing the transmission of control codes for setting up said signaling system as required for the release of said electric lock, means controlled by each signal clearing relay when released for preventing the control of the corresponding signal control relay by codes transmitted by switch lever operation regardless of the position of the corresponding signal lever, and means controlled by each signal clearing relay when energized for preventing the code control of said signaling system as required for the release of said electric lock.

12. In combination with a stretch of single track railway including a hand throw switch equipped with an electric lock and having entering signals at each end; a signal lever and a signal clearing relay for each signal, a switch lever and a repeating relay for the switch, all located at a control office, a reversible signaling system arranged to be energized at either end of the stretch to control the signal at the other end in accordance with traffic conditions in the stretch, means controlled from the office for reversing the direction of said signaling system effective only when the stretch is unoccupied and said repeating and signal clearing relays are released, a circuit for energizing each signal clearing relay controllable by its lever provided the corresponding traffic direction is established and said repeating relay is released, means for controlling the signal for the corresponding direction in accordance with the condition of said signaling system and the position of its lever rendered effective upon the energization of the associated signal clearing relay, means for energizing said repeating relay in response to the operation of said switch lever effective only when both signal clearing relays are released, means controlled by said repeating relay when energized for energizing said signaling system at both ends, and means at the switch location controllable by said signaling system when energized at both ends for releasing said electric lock provided the stretch is unoccupied.

13. In combination with a stretch of single track railway having entering and leaving signals at each end, a code system of communication having a station at each end of the stretch and means at a control office for transmitting codes to said stations to govern the clearing of said signals, a reversible signaling system for controlling one of said entering signals or the other, according to the direction established thereby, in accordance with traffic conditions in said stretch, a manually operable signal lever and a code starting button at the office for each station, means responsive to the operation of each starting button for initiating the transmission of a code for controlling the entering or leaving signal at the corresponding station in accordance with the position of the signal lever for such station,

means effective under selected conditions for initiating the transmission of a code to one station to effect the reversal of said signaling system in response to the operation of the starting button for the other station for clearing the entering signal at said other station, the transmission of such code occurring only if the traffic direction established by said signaling system at the time is the opposite to that which is required in order to clear the entering signal at said other station, and means including a signal clearing relay for each leaving signal controlled jointly by the signal lever for the corresponding station and by the associated starting button for rendering each code transmitted to the corresponding station effective to control said leaving signal if and only if such code is initiated by the operation of said associated starting button.

14. Direction selecting apparatus for a stretch of railway track equipped with a reversible signaling system having an entering signal at each end with a control relay for clearing such signal in accordance with traffic conditions in said stretch as manifested by said signaling system when set up in the corresponding direction, together with means for establishing control channels between a central office and stations at the ends of the stretch for the manual control of said signal control relays and of said signaling system, and for also establishing indication channels controlled by said signaling system for indicating traffic conditions at said office, in combination, electroresponsive means at said office for designating the direction of traffic movements and for

- 5 at times reversing said signaling system, a signal clearing relay at the office for each entering signal effective when operated to establish the channel over which the control relay for such signal is controlled, manually controllable means governed by said electroresponsive means for selectively operating that one of said signal clearing relays which is associated with the entering signal for the direction designated by said electroresponsive means, means for operating the control relay controlled over said channel to its signal clearing position, means controlled by said signaling system for automatically restoring said signal control relay and said signal clearing relay 10 to normal when a train governed by the signal controlled thereby enters the stretch, and manually controllable means for operating said electroresponsive means to change the designated traffic direction effective only when said signaling 15 system indicates that the stretch is unoccupied and both signal clearing relays occupy their normal positions.
